FIG. 1 is a perspective view of a two-stage LED light module showing the new design;

FIG. 2 is a right side view thereof.

FIG. 3 is a left side view thereof.

FIG. 4 is a front view thereof.

FIG. 5 is a back view thereof.

FIG. 6 is a top view thereof.

FIG. 7 is a bottom view thereof.

FIG. 8 is a side view of a two-stage LED light module mounted on a street post; and,

FIG. 9 is a perspective view thereof showing the back plate removed for ease of illustration only.

The back plate, street post and the housing (shown in phantom) in the figures do not form part of the design.
